UNITED STATES PATENT OFFICE.

JOHN A. PILCHER, OF ROANOKE, VIRGINIA.

COUPLER YOKE.

Application filed September 1, 1922, Serial No. 585,773. Renewed January 20, 1928.

This invention relates to railway cars and draft gears therefor.

One object of the invention is to provide a coupler yoke attached to a coupler in such manner to permit relative angling of the coupler.

Another object of my invention is to provide a coupler yoke which may be interlocked with a coupler by angular movement of one 10 relative to the other.

My invention also consists in the cooperation and arrangement of parts which I shall hereinafter describe and claim.

This application is a continuation in part of 15 my co-pending application filed April 18, 1921, Serial Number 462,082.

In the accompanying drawings Figure 1 is a plan showing a yoke and coupler embodying my invention in position in the under- 20 framing of a car; Figure 2 is a side elevation thereof; Figure 3 is a plan showing how the cushioning mechanism may be inserted into the yoke before applying to car.

The yoke is comprised of an upper arm 1 and a lower arm 2, joined at their rear end with vertically extending portions 2'. Each arm has a vertically disposed slot 3 extending therethrough of substantially the same width from the forward end of the upper arm 1 all 30 the way around to the forward end of the lower arm 2. The coupler butt 4 on its top and bottom surfaces is provided with circular extension 5, each of which has laterally extending lugs 6 arranged at right angles to 35 the axis of the coupler. The ends of the slots 3 in the yoke arms are arc-shaped and provide bearings 7 for the trunnions 5 on the coupler butt thereby providing substantial pulling bearings between the coupler and the yoke and at the same time allowing the 40 coupler freedom for lateral movement. The rear face of the coupler butt 4 and the forward face of the front follower block 8 preferably have corresponding arc-shaped faces 9 to permit the stresses of buffing to be transmitted directly from the coupler to the cushioning mechanism 10 regardless of the particular position to which the coupler may angle laterally with respect to the yoke. The tangential 45 surfaces 11 leading away from the arc-shaped forward face 9 of the front follower block serves to guide the coupler butt back into position after it has been pulled away from the follower during draft. The corresponding 55 arc-shaped faces 9 on the rear face of the coupler butt and the forward face of the front

follower also allows the front follower to be rotated about the coupler butt thus permitting the easy insertion of the cushioning mechanism 10 in the yoke. 60

The coupler and yoke are connected before either is placed in the car by swinging the coupler at right angles to the yoke and turning it on its side. The coupler butt when turned on its side, may be slipped between 65 the yoke arms 1 and 2, and then by using the rounded portion 12 of the coupler butt adjoining the trunnion under the lugs 6, be brought back to its normal vertical position, when lugs 6 will pass through the slots 3 in the upper and lower arms. The coupler may then 70 be turned into longitudinal alignment with the yoke, thus locking the coupler butt to the upper and lower arms of the yoke with the lugs 6 upon the trunnions 5. The front follower 8 may then be placed in position with 75 its forward face 9 bearing against the rear face of the coupler butt. The rear follower 13, which may be of any approved form is then placed against the forward face of vertically extending portions 2' of the yoke. 80

To insert the cushioning mechanism into the yoke the front follower 8 is rotated about the coupler butt, as shown in Figure 3, and the cushioning mechanism placed partly in 85 position between the yoke. From this position the cushioning mechanism may be pushed into its normal position, rotating the front follower back into its normal position. This will put the cushioning mechanism under 90 slight compression and cause the front follower to fit snugly against the coupler butt. 95

After the cushioning mechanism has been placed in position, the coupler, yoke, front and rear follower and the cushioning mechanism are then elevated into position on the car. Beneath the coupler butt and the yoke is a bottom plate 14, detachably fastened to the car frame, which forms a bearing for the lower lug 6, supports the coupler butt and also 100 holds the upper lug 6 near the top plate 15, thereby limiting the vertical movement of the coupler butt. The rear end of the yoke is supported by the carrier iron 16 which may be integral with or fastened to the bottom cover 105 plate 14.

The rear faces of the forward draft sill stops 17 are tapered slightly, as is the front face of the front follower block 8 which comes in engagement with the stops, as shown in 110 Figs. 1 and 2. This will allow the front edges of the front follower block 8 to enter the space

clear of the edges of the stops and thereby permit the easy application of the mechanism to the car after the cushioning mechanism has been placed within it.

5 Although I have herein shown and described what I consider the preferred manner of carrying out the invention, the same is merely illustrative and I contemplate all changes and modifications that come within 10 the scope of the claims appended hereto.

I claim:

1. In a device of the character described, a coupler yoke, having slotted upper and lower arms, a coupler, trunnions on the top 15 and bottom faces of the coupler butt projecting through the slots in the yoke arms, plates above and below the yoke, the plate below engaging the bottom trunnion supporting coupler and yoke and holding the top trunnion 20 near the top plate, thereby limiting the vertical movement of coupler butt.

2. In a device of the character described, a coupler yoke in the form of an elongated link with the ends bent in parallel planes to 25 form the upper and lower arms, a coupler, the butt thereof having slot and projection engagement with the forward ends of the yoke arms, a cushioning mechanism having a front and a rear follower, said coupler being disengagable from said yoke when substantially 30 at right angles to its normal position and turned on its side through an angle of approximately ninety degrees.

3. A coupler yoke having slotted upper 35 and lower arms, a coupler, the butt thereof having a slot and projection engagement with the forward ends of the yoke arms, a cushioning mechanism, a front and a rear follower, the slot in the yoke arms extending from the 40 slot and projection engagement of the coupler in the upper arm around the rear follower to the slot and projection engagement of the coupler in the lower arm.

4. A coupler yoke having slotted upper and lower arms, a coupler, the butt thereof having a slot and projection engagement with the forward ends of the yoke arms, a cushioning mechanism, a front and a rear follower, the butt of said coupler being so formed that all 45 points on its rear surface lie in a surface of revolution, and the forward face of said front follower being formed to cooperate with the rear face of said coupler butt, whereby said front follower and coupler may rotate relative to each other.

5. A coupler yoke comprising a plurality of U-shaped members having integral connections at their front ends, the said connections forming rotative bearings for the coupler butt.

6. A coupler yoke having upper and lower yoke members, each of which is comprised of parts arranged in parallel in a horizontal plane, said parts having integral connections at their front ends, the said connections forming rotative bearings for the coupler butt.

7. A one-piece compound yoke having upper and lower members, said upper and lower members being divided vertically along the longitudinal middle plane of the yoke, the 70 divided members being connected only at points of rotative engagement with the coupler.

8. A coupler yoke having slotted arms, a coupler, the butt thereof having an arc-shaped rear face and a slot and projection engagement with the forward ends of the yoke arms, a cushioning mechanism seated in said yoke, and a number between coupler and cushioning mechanism having an arc-shaped forward face cooperating with the rear face of the butt and adapted to transmit buffing stresses from coupler to cushioning mechanism approximately at the axis thereof when the coupler is angled laterally.

JOHN A. PILCHER.
